UNITED STATES PATENT OFFICE.

ALBERT S. MARKS, OF PHILADELPHIA, PENNSYLVANIA.

DESIGN FOR A BOX.

SPECIFICATION forming part of Design No. 30,980, dated June 13, 1899.

Application filed May 16, 1899. Serial No. 717,097. Term of patent 7 years.

To all whom it may concern:

Be it known that I, ALBERT S. MARKS, a citizen of the United States, residing in the city and county of Philadelphia, State of Pennsylvania, have invented and produced a new and original Design for a Box, of which the following is a specification, reference being had to the accompanying drawings, forming part thereof.

10 The leading feature of my design for a box is a box consisting of a body having a bridge on the inclined walls thereof.

Figure 1 represents a side elevation of a box embodying my design. Fig. 2 represents 15 a section thereof on line x x , Fig. 1.

In the drawings, A designates the body of a box, consisting of the base B, the inclined walls C, open at one end, and the bridge D on the top of said walls.

Having thus described my invention, what I claim as new, and desire to secure by Letters Patent, is--

The design for a box substantially as shown and described

ALBERT S. MARKS.
